INDEX OR FILING SYSTEM

Application filed May 15, 1928, Serial No. 277,812. Renewed December 8, 1931.

The object of my invention is to provide a simple card holder for use in filing and indexing systems. The card-holding member is preferably made of a transparent material, such as celluloid, which is bent or formed into a shape which will cause it to removably hold one or more cards and which will itself retain its shape in the ordinary uses of such devices. The holder is adapted to retain one or more cards used in indexing, accounting, billing or for any other purpose, and the holder may be grouped with many similar holders and mounted in a filing device, although the latter forms no part of the present invention. The material of the holder, being transparent, permits the reading matter on the card to be seen either from the front or back of the holder.

In addition, my improved device may be used as a single holder for holding one card, or it may be made to hold two cards, one on each side of the main wall of the holder, and in each case the card or cards may be readily removed for the purpose of writing, printing, or otherwise adding reading matter to the card or cards. In addition to the principal card or cards the device in one form is adapted to hold a strip on which the name or names or other indexing material may be supplied separate from the main card or cards.

In addition, I have provided in one form of the invention transparent sliders adapted to co-operate with the index strips for indicating index numbers or other matter on the strips. Other features and advantages will be set forth in the following detailed description of my invention.

In the drawing forming part of this application,

Figure 1 is a face view of a card holder embodying my invention in a form adapted for holding a single card together with an index or name strip,

Figure 2 is a sectional view thereof taken on the line 2—2 of Figure 1,

Figure 3 is a face view of a card holder adapted for holding two cards, together with an index or name strip, and

Figure 4 is a sectional view taken on the line 4—4 of Figure 3.

Referring first to the form of the invention shown in Figures 1 and 2, there is a sheet having a main portion 1 of transparent material which may be bent into the desired shape and which material will retain its shape during the handling incident to devices of this kind.

For this purpose I prefer to form the sheet 1 of celluloid of sufficient thickness to accomplish the purpose stated. The sheet is bent along one edge and folded to provide a loop 2 which receives through it and across the sheet a bar or rod 3 by which the holder may be hingedly secured to a member 4 of the filing device, so that the holder may be swung upon this pin to expose either side in reading position and to separate various holders in a group, it being understood that in practice a number of such holders will be generally grouped like pages in a book, to be turned on the rods 3. In my co-pending application Serial No. 277,813 of even date herewith I showed and described a device for holding a group of card holders such as those shown and claimed herein. The turned-over portion of the sheet is preferably secured by means of eyelets 5 passing through the two layers of the sheet to secure them around the rod 3. The free edge 6 of the folded sheet overlaps a portion of the main part 1 of the sheet so that one edge of the card 7 may be inserted between these two members.

The bottom edge of the sheet 1, as viewed in Figure 1, is bent to form a loop 8 and it then partially returns upon itself at 9 to form with the sheet 1 a pocket into which the lower edge of the card 7 may be inserted. From there the sheet is again bent to form a loop 10 and from there it extends downwardly at 11, preferably parallel with the main portion 1 and it is again bent to form a loop 12 and it then extends upwardly at 13 parallel with the portion 11. The portion 11 and the portions 9, 13 form a pocket into which may be inserted, endwise, a strip or card 14 on which may be printed or written a name indicating, for instance, the name of the customer whose record card 7 is held by this particular holder.

These name strips, indexes or targets 14

may remain in the holders and form a means of identifying each particular holder, whereas the cards 7 may be renewed or replaced from time to time. Printing, writing or other matter may be placed upon either or both surfaces of the card 7. That which may be placed on the uncovered surface of this card will naturally be visible or readable on one side, and any similar matter placed on the opposite side of the card will be readable through the sheet 1 because the latter is transparent. Likewise, names or other matter may be placed on both surfaces of the strip 14 to be read in either position in which the holder

10 may be placed, in one case by reading through the wall 11 which is transparent, and in the other case through the wall 13 which is also transparent.

From the above it will be apparent that the 20 holders may be arranged like leaves in a book to be turned back and forth and the cards held in the holders will be readable from either side. When the card 7 has been filled or when for any other reason it is desired to replace it, 25 it is merely necessary to bend the card 7 outwardly at the middle to withdraw the upper and lower edges respectively from between the edge 6 and the main portion 1 of the sheet and from the socket formed between the member 9 and the main portion of the sheet. The 30 reverse operation is performed in returning the card to the holder.

In Figures 3 and 4 I have shown the device adapted for holding two cards, together 35 with two name strips or targets. Herein the main sheet 1 is curved adjacent one edge to form the loop 15 which receives therethrough the holding wire 16 and the sheet then extends downwardly at 17 to overlap the main portion 40 of the sheet and to form a pocket to receive one edge of the card 17.

At 18 the sheet is bent or folded and is returned upon itself at 19 and thence around the loop portion 15 and the free edge 20 extends downwardly adjacent one face of the main portion 1 of the sheet to form a second pocket to receive the upper edge of another card 21 placed on the opposite side of the sheet to the first mentioned card 17.

50 At the bottom of the sheet 1 the material is bent to form a loop 22 and from there it passes upwardly at 23 adjacent one face of the main portion 1 of the sheet and is then folded at 24 and it passes downwardly at 25 and is thence curved laterally at 26 to extend around the loop 22. The sheet is then bent upwardly again at 27 and extends vertically at 28 and is thence folded in a loop at 29, and returned downwardly at 30. It is then again folded at 31 and extends upwardly at 32 parallel with the main portion of the sheet and is again bent to form a loop at 33 and it again extends downwardly at 34. This shaping of the 55 lower portion of the sheet provides a pocket

at one side of the main portion of the sheet to receive the lower edge of the card 17, the upper edge of the card, as stated, being received in the upper pocket. There is also formed a pocket on the opposite side of the 70 main portion of the sheet between the wall 32 and the main portion 1 to receive the lower edge of the card 21 placed adjacent the right hand surface of the main portion of the sheet as shown in Figure 4. There is also provided a pocket between the wall 32 and the parallel portions 30, 34 to receive endwise therein the strip 35 having the name or other identifying means for the holder.

I have shown staples 36 at opposite sides 80 of the holder for retaining the upper folds of the sheet and similar staples 37 at opposite sides of the bottom for retaining the folds in the relation indicated. With this type of holder cards may be placed in the pockets at 85 both front and back of the sheet 1 each card being separately removable from its respective pocket. Thus, in this form of the invention two cards may be placed in the same holder and the name strip or identifying strip may also be placed in the same holder.

The drawing illustrates two of the forms which may be made to adapt the invention to the various uses but in each form it will be observed that the holder is so folded as to 90 provide pockets for receiving the edges of record strips or cards in such manner that the latter may be readily removed from the holder either by bending the card or strip, or by sliding it endwise of the holder.

The cards are so held in the holders that they may be slid sidewise therein when desired. The target members may remain attached to the holders when the main cards are temporarily removed to be typed or written upon, so that the holder will not lose its identification as might be the case if the identifying insignia were only on the main card and therefore the latter may be quickly returned to its correct holder.

11 The holders may be inexpensively made from celluloid or similar material. They are light in weight and very convenient to handle.

Having described my invention, what I claim is:

1. A card holder comprising a sheet folded upon itself at one edge to provide a loop, a hinge member extending through said loop, said edge of said sheet being folded back to overlap the main portion of the sheet to provide a pocket, the opposite edge of said sheet being folded over upon itself to form a second pocket, said pockets being adapted to receive therein the opposite edges of a card placed parallel with the main portion of said sheet.

2. A card holder comprising a sheet of transparent material folded upon itself along one edge to form a pocket between the folded

edge and the main portion of the sheet to receive the edge of a card therein, the opposite side of said sheet being folded upon itself to provide a second pocket between said last-mentioned folded portion and the main portion of the sheet to receive the opposite edges of said card and fastening members passing through said folded portions of the sheet.

3. A card holder comprising a sheet having one edge portion bent back and forth upon itself to form portions overlapping the main portion of the sheet on both surfaces of the latter to form a plurality of pockets on opposite sides of the main portion of the sheet to receive therein the edges of cards disposed on opposite sides of the main portion of the sheet, and means adjacent the opposite edge of said sheet to engage the opposite edges of both of said cards.

4. A card holder comprising a sheet having one edge portion folded over said sheet to form a loop and to form a strip overlapping the main portion of the sheet to provide a pocket for the reception of the edge of a card, a hinge member passing through said loop, said edge being folded back upon itself and upon the opposite side of the main portion of the sheet to form a second pocket for the reception of the edge of a card disposed on the opposite side of the main portion of the sheet to said first card, and means at the opposite edge of said sheet for engaging the opposite edges of both of said cards.

5. A card holder comprising a sheet having one edge thereof bent back and forth upon itself and upon the main portion of the sheet to provide pockets for the reception of the edges of cards disposed on opposite sides of the main portion of the sheet, the opposite edge of said sheet being folded back and forth upon itself and upon the main portion of the sheet to provide a plurality of pockets to receive therein the opposite edges of said cards.

45 6. A card holder comprising a sheet having means at one edge to engage the edges of cards placed on opposite sides of the main portion of said sheet, the opposite edge of said sheet being folded back upon the main portion of the sheet to provide pockets for the reception of the opposite edge of one of said cards, thence folded back upon itself and across the end of the main portion of the sheet, and being thence folded back and forth upon itself and upon the main portion of the sheet to form a second pocket to receive the edge of a card placed on the opposite edge of the sheet to said first mentioned card, and also forming a third pair of opposed pockets to receive therein opposite edges of a third card.

7. A holder for cards comprising a sheet folded upon itself at one edge to provide a loop, a hinge member extending through said loop, said folded edge of said sheet over-

lapping the main portion of said sheet to provide a pocket, the opposite edge of said sheet being folded over upon itself to form a second pocket, said pockets being adapted to receive therein the opposite edges of a card placed parallel with the main portion of said sheet.

8. A card holder formed of a sheet of material, said sheet being folded along one edge back upon itself whereby the folded portion and the main portion of the sheet form a pocket for the reception of the edge of a card therein, said edge being folded back on the sheet to form a second pocket to receive the edge of a second card placed against the opposite face of said sheet to said first card, the opposite edge of said sheet being first folded back upon itself to form a third pocket for the reception of the opposite edge of said first card, said latter edge of said sheet being thence folded in a reverse direction to form a fourth pocket for the reception of one edge of said second card.

Signed at the city, county and State of New York, the 24th day of April, 1928.
